J. LAPSHANSKY

CUTTER BAR JACK

Filed Sept. 8, 1924

Inventor

J. Lapshansky

By Clarence A. O'Brien.

Attorney

UNITED STATES PATENT OFFICE.

JOHN LAPSHANSKY, OF NOKOMIS, ILLINOIS.

CUTTER-BAR JACK.

Application filed September 8, 1924. Serial No. 736,611.

To all whom it may concern:

Be it known that I, JOHN LAPSHANSKY, a citizen of the United States, residing at Nokomis, in the county of Montgomery and State of Illinois, have invented certain new and useful Improvements in Cutter-Bar Jacks, of which the following is a specification.

This invention relates to a new and improved jack, which I have specially designed for use in conjunction with the cutter bar on a conventional coal cutting machine.

What I aim to do is to modify the usual shoe, with its tilting and levelling standard, the standard in the present instance being provided with a toothed rack, with which a rotatably mounted pinion is adapted to mesh, for raising and lowering the cutter bar to a desired elevation, the pinion being rotated by novel and conveniently located means.

It is a feature of the invention to arrange the pinion and its operating means within a recess formed in the usual yoke and to cover these with a protecting plate, so that they may not become disarranged or injured.

Other features and advantages of the invention will become apparent from the following description and drawing.

20 In the accompanying drawing, forming a part of this specification, and in which like numerals are employed to designate like parts throughout the same:

Figure 1 is a top plan view of a portion 35 of the cutter bar, with a jack constructed in accordance with the present invention.

Figure 2 is a transverse section, taken on the plane of the line 2—2 of Figure 1, looking in the direction of the arrows.

40 Figure 3 is a section, taken on the line 3—3 of Figure 1.

Figure 4 is a section, taken on the line 4—4 of Figure 1.

In the drawings, the conventional cutter bar is designated by the reference character 1. As is usual, this bar is provided with an elongated guide slot 2, to accommodate the standard 3 of the jack. Extending crosswise of the upper side of the cutter bar is a cross piece 4 which is commonly referred to as a yoke. Although I have not shown it, this yoke is slidably connected to the cutter bar, so that when it is lifted the cutter bar will be lifted with it. I have

55 shown the yoke equipped with chain guards 5. In carrying out the present invention,

the yoke is provided in its top with a specially shaped recess to accommodate the parts of the jack. It is also provided with a bore 6, which intersects the recess, and serves to accommodate the standard 3 of the jack. This standard is pivotally connected as at 7 between the centrally disposed lugs of a cup shaped base 8, frequently referred to as a shoe. Obviously this shoe is adapted to rest on the mine floor and the pivotal connection of the standard permits tilting and levelling of the cutter bar. As before intimated, one edge of the standard is provided with a plurality of rack teeth 9. Meshing with these rack teeth is a small pinion 10, keyed upon the horizontal shaft 11, journaled in appropriate bearings provided in the aforesaid recess. Also keyed on the shaft and located at the opposite end is a small gear 12, with which the threads of a worm 13 meshes. The worm is disposed vertically and is rotatably mounted in the specially formed portion of the recess provided, and has its shank 14 extending through an opening formed in the cover and protecting plate 15. The extremity of the shank is flat faced to permit a wrench to be connected thereto. The cover plate extends over the pinion, gear and shaft, together with the threads of the worm, and serves to fully protect these parts. It may be held in place by screws or the like.

It is quite clear that by engaging a wrench with the flat faced portion of the shank 14 of the worm and rotating the latter, the shaft 11 will be rotated. As this carries the pinion 10, the rotation of the latter, which is in mesh with the rack teeth will raise and lower the cutter bar. As the cutter bar moves into and under the coal, the jack and yoke will remain stationary, this being permitted by the elongated slot 2.

It occurs that the foregoing description if read carefully with the drawings will suffice to enable a clear understanding of the invention to be attained. Therefore, a more detailed description is thought unnecessary.

I claim:

A device of the class described comprising 105 a cutter bar provided with an elongated guide slot, a yoke extending crosswise of the top of said cutter bar and in slidable contact therewith, said yoke being provided with a vertically disposed bore in alignment 110 with said slot, the upper side of the yoke being recessed, a cover plate for said recess,

a base located beneath said cutter bar, a standard pivotally connected to said base and rising therefrom and extending slidably through said slot and then through said bore, one edge of said standard being provided with rack teeth, a shaft rotatably mounted in the aforesaid recess and provided on one end with a pinion in mesh with the teeth of said rack, and at its opposite end with a gear, a vertically disposed and

rotatably mounted worm also located in said recess, and having its threads engaging the teeth of said gear, the shank of said worm extending through an opening in the aforesaid cover plate and having its extremity ¹⁵ fashioned to permit engagement of the wrench therewith.

In testimony whereof I affix my signature.

JOHN LAPSHANSKY.
